UNITED STATES PATENT OFFICE

CHARLES M. HEID, OF ERIE, PENNSYLVANIA

EDUCATIONAL DEVICE

Application filed April 22, 1931. Serial No. 532,076.

This invention relates to educational devices and more particularly to a device constructed to explain the movements of earth, sun and moon.

5 It is the object of the present invention to provide a device of the above mentioned character capable of being supported in an upright position, and including spherical shaped bodies representing the earth, sun and moon, together with a novel construction of means for moving the same, to illustrate the earth turning on its axis, and its movements around the sun, the moon's travel around the earth, and the node period of 15 the moon.

The nature and advantages of the invention will be better understood when the following detail description is read in connection with the accompanying drawings, the invention residing in the construction, combination and arrangement of parts as claimed.

In the drawings forming part of this application like numerals of reference indicate 20 similar parts in the several views and wherein:

Figure 1 is a view in elevation of the device.

Figure 2 is a view taken at a right angle 25 to Figure 1.

Figure 3 is an enlarged fragmentary sectional view of the upper part of the device.

Figure 4 is a similar view of the lower 30 part thereof.

Figure 5 is a fragmentary sectional view.

Figure 6 is a view of the sign disk.

The device forming the subject matter of the present invention is adapted to be supported in a vertical position on a standard 10 35 10 provided with a suitable base (not shown).

Secured to one side of this standard adjacent its upper end is a substantially U-shaped bracket 11. Journaled in the standard 10 and extending through the bracket 11 is a shaft 12 supporting on its outer end a sphere 13 representing the sun. The shaft 12 is rotated by a crank handle 14 arranged at the rear of the device. Also loosely mounted on the shaft 12 directly behind the sun 13 is a disk 15 having a weight 16 to hold the same in proper

position. One side of this disk is provided with the months of the year, and the different seasons as illustrated in Figure 1.

Rotatably mounted on the shaft 12 is a hollow shaft 17 which carries the section 18 of an adjustable arm, the other section 19 being slidably associated with the section 18, and held fixed relatively thereto by a wing nut and bolt. The upper end of this arm carries a sleeve 20 forming a bearing for a hollow shaft 21, which supports a frame-like structure 22. Positioned within the shaft 21 is a hollow shaft 23 formed with a shoulder 24 bearing against the frame 22, while projecting from the shoulder is an arm 25 constituting a bearing for the shaft 26. Carried by the outer end of the shaft 26 is a sphere representing the earth and indicated at 27. Keyed to the shaft 26 is a bevel gear 28 meshing with a similar gear 29 fixed to the adjacent end of the shaft 30 rotatably mounted within the hollow shaft 23. Rotation is imparted to the shaft 30 in a manner to be presently described, thus representing rotation of the earth about its axis.

For this purpose I preferably employ a sprocket 31 keyed to the shaft 12 and trained over this sprocket and a relatively smaller sprocket 32 is an endless chain 33. The sprocket 32 is keyed on a stub shaft 34 journaled in a bearing 35 of the arm section 19 above referred to. Carried by one end of the shaft 34 is a gear 36 which meshes with a gear 38 on the shaft 30. Manifestly, when the shaft 12 is rotated by the crank 14 rotary motion is imparted to the shaft 30, thereby rotating the shaft 26 and its sphere, to represent the earth turning about its axis.

For moving the earth about the sun I employ a gear 39 keyed to the shaft 12 and meshing with a larger gear 40 carried by the shaft 41 journaled in the standard 10 and bracket 11. Also carried by this shaft 41 is a smaller gear 42 keyed on the hollow shaft 17. Consequently when the crank handle 14 is operated, rotation is imparted to the hollow shaft 17 which carries the arm, the section 19 of which supports the shaft 21, so that the entire mechanism is rotated about the sun. One rotation of the adjustable arm 100

represents one year. A counterweight 37 is carried by the extension rod as shown.

In order to move the moon around the earth, I provide a gear 44 connected with the sprocket 32 by a hub 45, and which gear 44 meshes with a gear 46. The hub 47 of the gear 46 is rotatably mounted on the hollow shaft 21, and said hub also carries a bevel gear 48. This latter mentioned gear meshes with a smaller bevel gear 49 keyed to the shaft 50 journaled in the frame 22. The shaft 50 supports a gear 51 meshing with the internal teeth 52 of a ring gear 53 supported between a plurality of grooved rollers 54 carried by the frame 22. Projecting from the ring gear are spider arms 55 which support an annulus 56 on which is mounted the sphere 57 representing the moon. The annulus 56 not only supports the sphere, but is employed to clearly illustrate the angle at which the moon is traveling with relation to the earth's orbit, and the moon's path not only when in motion, but also when at rest. Obviously when the shaft 50 is rotated by reason of its association with the mechanism, gear 51 rotates the ring gear 53 together with the moon supporting annulus.

The node period and serpentine movements of the moon are provided by a sprocket 58 supported by the hub 59 supported by the bracket 11 and sprocket 60 carried by the hollow shaft 21 over which is trained an endless chain 61. To keep the sphere representing the earth at the same vertical position while traveling its course around the sun, I employ a sprocket 62 mounted on the hub 58 of the bracket 11 and over which and sprocket 63 keyed to the shaft 23 is trained an endless chain 64, both sprockets 62 and 63 being of the same size. Manifestly I have devised a novel construction of means for illustrating the relative movements of the earth, sun, and moon, and control the same from a single operating handle.

While it is believed that from the foregoing description the nature and advantages of the invention will be readily apparent, I desire to have it understood that such changes may be resorted to when desired as fall within the scope of what is claimed.

What is claimed is:

1. A device of the character described comprising a rotatable shaft, a sphere carried thereby representing the sun, means for rotating said shaft, a hollow shaft rotatably mounted on the first mentioned shaft, an adjustable arm supported by the hollow shaft, mechanism supported by the outer end of said arm including a sphere mounted for rotation and representing the earth, means operated from said shaft for rotating the earth about its axis, a frame, a ring gear rotatably supported on said arm, a ring-like member carried by the ring gear, a sphere representing the moon supported by the ring-like

member for rotation therewith about the earth, means operated from said shaft for rotating the ring gear, and means operable from said shaft for rotating said arm and the mechanism carried thereby about the sun.

2. A device of the character described comprising a rotatable shaft, a sphere carried thereby representing the sun, means for rotating said shaft, a hollow shaft rotatably mounted on the first mentioned shaft, an arm supported by said hollow shaft, mechanism supported by the outer end of said arm and including a sphere mounted for rotation and representing the earth, means operated from said shaft for rotating the earth, a hollow shaft journaled in the outer end of said arm, a frame carried by said shaft, a sphere representing the moon supported by said frame for movement about the earth, means operated from the first mentioned shaft for rotating the moon about the earth, and means operated from the first mentioned shaft for rotating the arm, and said mechanism supported thereby about the sun.

3. A device of the character described comprising a vertically disposed standard, a shaft journaled thereon, a handle for rotating the shaft, a sphere carried by the shaft and representing the sun, an arm rotatable about said shaft and including a counterbalancing weight, a bearing formed on the outer end of said arm, mechanism supported by said arm and including a sphere mounted for rotation and representing the earth, means for rotating said earth including a shaft operated from the first mentioned shaft, a hollow shaft rotatably supported by the second mentioned shaft, a frame carried by the second mentioned shaft, a ring gear rotatably mounted on said frame, a sphere carried by the ring gear and representing the moon, means operable from the first mentioned shaft for rotating the moon about the earth, and means operated from the first mentioned shaft for rotating said arm and the mechanism carried thereby about the sun.

4. A device of the character described comprising a rotatable shaft, a sphere carried thereby and representing the sun, means for rotating said shaft, a hollow shaft rotatably mounted on the first mentioned shaft, an adjustable arm carried by the hollow shaft, a counterbalancing weight associated with said arm, mechanism supported by the outer end of the arm and including a stub shaft mounted for rotation, a frame, a sphere mounted for rotation in advance of the frame and representing the earth, means operated from the first mentioned shaft for rotating said earth, a ring gear rotatably supported on said frame, a sphere supported by the ring gear for movement therewith about the earth and representing the moon, means for rotating said ring gear from the

first mentioned shaft and including said stub shaft, and means operated from the first mentioned shaft for rotating said arm and the mechanism supported thereby about the sun.

- 5 5. A device of the character described comprising a vertically disposed standard, a shaft journaled thereon, means for rotating the shaft, a sphere carried by the shaft and representing the sun, an arm rotatable about the shaft and including a counterbalancing weight, mechanism supported by said arm and including a sphere mounted for rotation and representing the earth, a frame, spaced rollers supported by the frame, a ring gear rotatably mounted on said rollers, a ring-like member carried by said gear, a sphere supported by the ring-like member and representing the moon, means operable from the first mentioned shaft for moving the moon around the earth, and means operated from the first mentioned shaft for rotating said arm and the mechanism supported thereby about the sun.
- 25 6. A device of the character described comprising a standard, a shaft journaled thereon, means for rotating the shaft, a sphere carried by the shaft and representing the sun, an arm rotatable about said shaft, a counterbalancing weight for said arm, mechanism supported by said arm and including a sphere mounted for rotation and representing the earth, a stub shaft mounted on said arm and rotated from the first mentioned shaft, means for rotating the earth from said stub shaft, a frame, rollers carried by the frame, a ring gear supported by said rollers, an annulus carried by the gear, a sphere supported by the annulus for movement about the earth, means operated from said stub shaft for rotating said ring gear, and means operated from the first mentioned shaft for rotating said arm and the mechanism supported thereby about the sun.

45 In testimony whereof I affix my signature.
CHARLES M. HEID.
